CLAIM

The ornamental design for an air freshener container, as shown and described.

DESCRIPTION

FIG. 1 is a top plan view of an air freshener container showing my new design;

FIG. 2 is a bottom plan view thereof; and,

FIG. 3 is a right side view thereof taken along line 3—3 of FIG. 1, the left side view being a mirror image thereof.

The surface(s) or portion(s) of the article not shown in the drawing or described in the specification form(s) no part of the claimed design.
